Charles J. Colling, Inventor

C. A. Snow, Esq.

UNITED STATES PATENT OFFICE.

CHARLES JOSEPH COLLING, OF CINCINNATI, OHIO.

HANDLE-BAR FOR BICYCLES.

SPECIFICATION forming part of Letters Patent No. 402,143, dated April 30, 1889.

Application filed February 13, 1889. Serial No. 299,773. (No model.)

To all whom it may concern:

Be it known that I, CHARLES JOSEPH COLLING, a citizen of the United States, residing at Cincinnati, in the county of Hamilton and 5 State of Ohio, have invented new and useful Improvements in Handle-Bars for Bicycles, &c., of which the following is a specification.

The invention relates to improvements in handle-bars for bicycles, tricycles, and other velocipedes, having for its object to prevent the jar and vibration of the forks and frame of the machine from being communicated to the handle-bar; and it consists in a certain novel construction and combination of devices, fully described hereinafter in connection with the accompanying drawings, and specifically pointed out in the appended claims.

In the drawings, Figure 1 is a perspective 20 view of a head of a machine to which the improved handle-bar is attached. Fig. 2 is a vertical central sectional view of the same.

Referring by letter to the drawings, A designates the head of the machine, of any ordinary shape, which is provided with the 25 lateral parallel ears B B, having registering perforations b b, and C designates the improved handle-bar, which is formed in two independent arms or sections, D D, which are fitted between the parallel ears B B and mounted on the transverse bolts E E, which are fitted in the registering perforations b.

The arms or sections of the handle-bar are provided adjacent to the head with the cross-heads F F, the upper and lower ends of which are slightly removed from the head A to permit a slight vertical swing of the free ends of the arms or sections. The head is provided in opposite sides with the recesses G G, in 35 which are fitted the rubber cushions H H, which normally hold the upper ends of the cross-heads of the handle-bar out of contact with the head, and in a transverse perforation, I, which is formed in the head below the ears C C, is fitted a strong coiled spring-cushion, K, which bears at its ends against the lower ends of the cross-heads.

The spring-cushion K is strong enough to hold the lower ends of the cross-heads out of 40 contact with the head of the machine; but it is obvious that all jar and shock of the head of the machine (which is communicated

thereto by the frame) will be lost or broken before it reaches the arms of the handle-bar.

The rubber cushions are designed to prevent the upper ends of the cross-heads from rattling against the head; but when it is desired to have a firm handle-bar, as in climbing hills, the upward pull on the ends of the arms or sections compresses the rubber cushions and brings the upper ends of the cross-heads in contact with the head.

Various devices have heretofore been employed to break the jar on the handle-bar on account of the annoyance to the rider which is caused thereby; but by forming the handle-bar in two arms or sections, which are jointed together, and are held out of contact with the head by cushions, this object is successfully attained by very simple means and with but 70 slight additional expense.

It will be seen that this construction does not interfere with the steering, as the arms are pivoted on horizontal bolts, and are therefore only capable of vertical movement. The 75 greater portion of the jar on the handle-bar is vertical.

Having thus described my invention, I claim—

1. In a velocipede, the combination, with 80 the head, of the handle-bar formed in independent arms or sections, which are pivoted to the head and are provided with cross-heads at their adjacent ends, and the cushions arranged between the ends of the cross-heads 85 and the head of the machine, substantially as specified.

2. In a velocipede, the combination, with a head provided with lateral parallel ears B B, of the handle-bar formed in independent 90 arms or sections which are pivoted between the said ears and are provided with cross-heads F F, the rubber cushions bearing against the upper ends of the said cross-heads, and the coiled spring-cushion bearing against 95 the lower ends of the said cross-head, substantially as specified.

3. In a velocipede, the combination, with the head provided in its opposite sides with the recesses G G, and having a transverse perforation, I, of the rubber cushions fitting in the said recesses, the coiled spring-cushion arranged in the transverse perforation, and the handle-bar comprising the independent arms 100

or sections D D, which are pivoted to the head, and are provided with cross-heads which bear at their upper and lower ends, respectively, against the rubber and the spring-cushions, 5 substantially as specified.

4. In a velocipede, the head, the handle-bar formed in independent arms or sections which are pivoted to the head, the rubber cushions H, bearing above the pivot-point of the arms 10 or sections, and the coiled spring K, bearing below the said pivot-point, as set forth.

5. In a velocipede, the head, the handle-bar formed in two independent sections pivoted

to the head and held out of contact therewith by means of separate and independent cushions which bear against the said sections, respectively, above and below the pivot-point thereof, as set forth. 15

In testimony that I claim the foregoing as my own I have hereto affixed my signature in 20 presence of two witnesses.

CHARLES JOSEPH COLLING.
